CLARENCE A. JORDAN AND CHESTER C. COON, OF OAKLAND, CALIFORNIA

POLE UNLOADER

Application filed January 11, 1930. Serial No. 420,138.

The invention is for a safety pole binder and unloader.

The objects of the invention are:

First: To provide a means whereby poles may be unloaded from a flat car with safety to the workmen.

Second: To provide a means as above described, which can be anchored in the stake pockets of a flat car, while the retaining stakes are in place with the load.

Third: To provide means as above described whereby the load can be held in place on the car while the bond wires and ties are cut and the stakes on the unloading side of the car removed.

Fourth: To provide a device as described with which, after cutting bonds and removing stakes, the load can be eased off the car without danger to the men unloading the car.

With these, and other objects in view which will become apparent from the drawings and as the description is set forth, the device consists of parts which will herein-after be more fully described, illustrated and claimed.

Referring to the accompanying drawings, in which:

Figure 1 is an end elevation of a standard railroad flat car, showing our invention in place, and easing off a load of poles.

Fig. 2 is a side elevation of an empty flat car with the invention in place after unloading the poles.

Fig. 3 is an end elevation of the car with the poles eased down and ready for removing from the car.

Fig. 4 is a perspective view of the invention.

Fig. 5 is an end elevation of a car load of poles before applying the device for unloading the poles.

In the accompanying drawings, similar reference characters are used to designate similar parts throughout the several views.

Reference character 1 indicates a flat car as used in railroad transportation and provided with a multiplicity of stake pockets 2 disposed along each side of the car 1, in which stakes 3 are usually disposed for re-

taining the poles 4 on the car while being transported. Bond wires 5 or similar means are used to bind two oppositely disposed stakes and prevent spreading of the stakes by the load of poles.

55

The parts so far enumerated are not a part of the invention.

The invention consists of a pivotal anchor member indicated as an entirety 6, and a stake indicated as an entirety 7. The anchor member 6 comprises a leg 8 adapted to slidably fit into the stake pockets 2, an aperture 9 being provided to receive a pin 10 below the lower edge of the pocket 2 to prevent the anchor member lifting out of the pocket during operation.

A shoulder 11 is provided to seat on the top edge of pockets 2.

The upper end of anchor member 6 is of forked construction as indicated and is provided with apertures 12 and 13 in cheeks 14, and 15, said apertures adapted to receive pins 16.

Stake 7 is provided with two apertures 17 adapted to register with apertures 13 and 12 in member 6, the member 18 being adapted to freely fit between cheeks 15 and 14. Member 18 is indicated as having the end 19 thereof fitted into a pipe 20, and retained by means of bolts or rivets 21. This part could readily be produced by flattening the end of pipe 20 to produce at the end thereof a flat portion to correspond to part 18. At the opposite end of member 7, a clevis 22 is provided, being hingedly related to the pipe 20 at 23.

85

The operation of the device is as follows: The device is used in pairs, not less than two pair being used to unload a car. With a car of poles as indicated in Fig. 5 spotted at the unloading location, the members 6 are placed in diametrically opposite pockets adjacent the ends of the car, in which no stakes are installed, it being customary to only provide about six stakes on each side of the load while there are usually 13 pockets on the side of a car. Poles over 40 foot length are usually loaded on two cars. Therefore, it will usually be found that removal of stakes will not be necessary for installation of the device.

After placing the anchor members 6 in

100

pockets 2, pins 10 are inserted in apertures 9, thus locking the members in the pockets.

Members 7 are hingedly connected at 13 with pins 16, on both sides of the car, raised to a vertical position alongside the load, and another pin 16 inserted through apertures 12 and 17, thus locking members 7 in a vertical position. Ordinary block and tackle consisting of sheave blocks 25 and 26 and a rope 27 are attached to the clevises 22 on oppositely disposed stakes 7, the sheave block 25 on the unloading side of the car preferably being attached to the clevis by a short length of rope 28. The whip 29 is drawn tight and held after removal of pins from aperture 12-17 from all stakes on the unloading side of the car. Bond wires 5 are cut and stakes 3 removed from the unloading side, the load of poles being retained in position by means of members 7 and block and tackle 27. Whips 29 are gradually slackened away, allowing the load to gradually ease away as indicated first in Fig. 1, to the position as indicated in Fig. 3. Block and tackle 27 is then removed, after which the poles are unloaded from the car.

A constant source of danger exists in present methods, where the bond wires are cut and the stakes cut away, the workmen depending mainly on agility for protection when the load starts. This danger is entirely obviated by my method.

It will be noted that various changes may be resorted to in the general arrangement and construction of the device, and parts, without departing from the spirit or scope of the invention or sacrificing any of the advantages thereof as set forth in the foregoing description and as defined in the following claims, therefore, we do not limit ourselves to the exact arrangement of said parts or to the details of construction as illustrated in the accompanying drawings.

We claim:

1. A pole unloader comprising an anchor member having a yoke formed at one end, the opposite end being adapted to fit into the stake pocket of a car, a stake member hingedly connected in said yoke, a locking pin, and aligning apertures in said yoke and said stake adapted to receive said locking pin.

2. A pole unloader comprising an anchor member having a yoke formed at one end, the opposite end being adapted to fit into the stake pocket of a car, a stake member pivotally mounted in said yoke, a locking pin, aligning apertures in said anchor member and said stake member spaced from the pivotal point and adapted to receive said locking pin, and a clevis pivotally connected to the opposite end of said stake member.

3. A pole unloader comprising an anchor member having a yoke formed at one end, the opposite end being adapted to fit into the stake pocket of a car, a stake member pivotally mounted in said yoke, a locking pin,

aligning apertures in said anchor member and said stake member spaced from the pivotal point and adapted to receive said locking pin, a clevis pivotally connected to the opposite end of said stake member, and a retaining pin removably disposed in an aperture adjacent the end of said opposite end.

In testimony whereof we have affixed our signatures.

CLARENCE A. JORDAN.
CHESTER C. COON.
